US0D1089211S

(12) **United States Design Patent** (10) **Patent No.:** **US D1,089,211 S**
(45) **Date of Patent:** ** *Aug. 19, 2025

(54) **DISPLAY MODULE**

(71) Applicant: **LG DISPLAY CO., LTD.**, Seoul (KR)

(72) Inventor: **Byeongseong So**, Paju-si (KR)

(73) Assignee: **LG DISPLAY CO., LTD.**, Seoul (KR)

(*) Notice: This patent is subject to a terminal disclaimer.

(**) Term: **15 Years**

(21) Appl. No.: **29/883,459**

(22) Filed: **Jan. 30, 2023**

Related U.S. Application Data

(63) Continuation of application No. 29/776,283, filed on Mar. 29, 2021, now Pat. No. Des. 980,203.

(30) **Foreign Application Priority Data**

Sep. 28, 2020 (KR) 30-2020-0046921

CLAIM

The ornamental design for a display module as shown and described.

DESCRIPTION

FIG. 1 is a front, right perspective view of the display module showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the figures depict portions of the display module that form no part of the claimed design.

1 Claim, 7 Drawing Sheets
